TYPOGRAPHICAL CASTING MACHINE

James G. McNamara, Brooklyn, N. Y., assignor
to Mergenthaler Linotype Company, a corpora-
tion of New York

Application June 24, 1933, Serial No. 677,417

34 Claims. (Cl. 199—52)

This invention relates to typographical machines, such as linotype machines of the general organization represented in U. S. Letters Patent to O. Mergenthaler No. 436,532, wherein circulating matrices are released from a magazine in the order in which their characters are to appear in print and then composed in line in an assembling elevator, the composed line transferred to a vertically movable transporter or first elevator which presents them to a mold, the mold filled with molten metal to form a slug or "linotype" against the matrices which produce the type characters thereon, and the matrices thereafter elevated and returned through a distributing mechanism to the magazine from which they started. More particularly, the invention is directed to an improved machine which is designed primarily for large or display matrices and which is adapted to be used for hand composition as well as machine composition; and to this end the improved machine is provided, in addition to a magazine or magazines for the machine composed matrices, with a storage tray for the hand composed matrices, which tray is conveniently arranged on the machine within reach of the operator, and from which the matrices may be readily selected and composed by hand in the assembling elevator. After composition (whether by hand or by machine), the line is transferred in the usual way to the vertically movable transporter or first elevator, which presents it to the mold for the casting of the slug and later delivers it to the second elevator which, in the improved machine, is arranged to be arrested in either of two different positions, one for transfer of a line of machine composed matrices to the regular distributing mechanism, and the other for the transfer of a line of hand composed matrices to a channel or guideway leading to the storage tray. The hand composed matrices are thus circulated through the machine in the manner of the machine composed matrices, and the present improvements are directed chiefly to the devices for adapting the new machine to take care of the hand composed matrices.

The improved machine is particularly adapted for use with standard "head letter" matrices (machine composed) ranging in size from 14 pt. to 36 pt., and with special matrices (hand composed) ranging in size from 36 pt. to 72 pt. In the commercial machines, the "head letter" matrices are composed at the lower level in the assembling elevator, and transferred at that level to the first elevator, which is then arrested in a raised position with reference to the mold. The improved

machine likewise makes provision for arresting the first elevator at two different levels, but the lower level corresponds to the normal upper level of the commercial machines to enable the standard matrices to cooperate with the standard molds, whereas the other level is still higher in order to present the special matrices to special or larger size molds.

The different levels of the first elevator are determined by an adjustable slide on the vise cap, which slide in one adjusted position is engaged directly by a banking screw in the elevator to arrest the elevator at the lower level for the standard matrices, and which in another adjusted position presents a stud or banking block thereon for engagement by said screw to arrest the elevator at the upper level for the special matrices. The "vise automatic" which functions to permit the machine to complete a cycle of operation, when the matrices are presented to the mold at the proper level, is operated through a plate, hinged to the slide, by a second screw on the first elevator, banking directly against the plate or against a stud carried by the plate depending upon the adjustment of the slide.

To avoid the improper setting of the slide and injury to the parts or metal "squirts", if, through inattention or mistake on the part of the operator, the improper mold is selected, the improved machine is provided with safety devices which render it substantially "fool-proof". Such safety devices contemplate a stop associated with the "intermediate channel" between the assembling elevator and the first elevator and which is manually adjustable to two positions. In one position, the standard matrices are allowed to be transferred to the first elevator and the special matrices blocked against transfer, and vice versa for the other position. The proper adjustment of the first elevator arresting slide on the vise cap is automatically determined by the adjustment of the aforesaid line stop.

Safety means are also provided to arrest the first elevator in advance of the casting level (and thus prevent presentation of the matrix line to the mold and the subsequent casting operation) in the event that an improper mold is selected to cooperate with the matrices composing the line being transferred to the elevator. In the preferred embodiment illustrated, these safety devices include an arresting finger, slidably mounted in the first elevator and adapted in one or another of its positions to clear or engage variant banking blocks associated with the different molds, depending upon whether the proper

or improper mold has been selected. The position of the finger is determined by the form of the matrices being transferred to the elevator, through the cooperation of the adjustable line 5 stop associated with the intermediate channel and the elevator arresting slide on the vise cap.

The special matrices are formed so as to be supported in the assembling elevator and the first elevator without requiring any changes 10 therein, the matrices for this purpose being provided with projecting ears on their front edges spaced the same distance from the top as the corresponding ears of the standard matrices, so as to be supported by the lower rails on the front 15 walls of the two elevators.

Other features of the improved machine include means for preventing the return of the assembler slide at the will of the operator, when it is desired to employ the machine for hand composition; and an improved galley stacker having an adjustable stroke to accommodate slugs of 20 different thicknesses, and which is determined automatically by the setting of the trimming knives.

In the accompanying drawings, the invention is shown merely in exemplified or preferred form and as applied to a linotype machine of standard 25 design, but obviously many changes and variations may be made therein and in its mode of adaptation without departing from its spirit. It should, therefore, be understood that the invention is not limited to any specific form or embodiment, except insofar as limitations are specified in the claims.

Fig. 21 is a front elevation of a portion of the machine, showing the common means for transferring the matrices from the second elevator to the distributor and storage tray.

As shown in Fig. 2, the machine is equipped with a channeled magazine A resting on a base frame A', and pivotally mounted in the machine, so that it may be moved into and out of operative relation with an assembler entrance or raceway B. The magazine in its operative position cooperates with a series of escapements A² fixed to the base frame and operated from the finger keys of a keyboard P through a series of power operated devices (not shown), and a corresponding series of intermediate reeds A³ to release the matrices, one at a time, from the magazine.

The released matrices are directed downwardly through the assembler entrance B and guided thereby onto a constantly driven inclined belt B' (Fig. 1) which delivers them, one after another, into the assembling elevator or assembler C, the latter comprising generally the front and rear side walls C¹, C², between which the matrices are 35 composed.

As the matrices enter the assembler C, they are stacked in line under the influence of a star wheel (not shown) which pushes them against a vertical finger c of a yielding line resistant slide C³.

When the matrix line is completely composed, the assembler C is raised into registration with the intermediate channel D through which the line, by the active stroke of the delivery slide E, is transferred horizontally from the assembler into 50 the vertically movable transporter or so called first elevator F. This latter operation starts the machine automatically, and the transporter is thereupon caused to descend with the line to the casting position, where it is supported and sustained upon a vise frame O in front of the active mold, the machine being usually equipped with several molds carried in a rotatable wheel or disc G which is adjustable at will to bring any selected mold into use. Preparatory to casting of the slug, the 55 mold disc G is advanced to carry the active mold into close contact with the matrix line, which is then justified after the intaglio characters thereof, by a slight upward movement of the transporter F (to engage the lower projecting ears of 60 the matrices with the lip of the mold) are aligned with the mold slot.

After the casting operation, the transporter F rises to its uppermost position for registration with the upper transfer channel H, and the mat- 75

rices are then transferred to the second elevator J, which carries them upwardly to the distributing level, the transporter F, meanwhile being returned to its normal position and the mold disc being given a three-quarter turn to carry the mold to the ejecting position.

As the cycle of operation is completed, the slug is ejected from the mold from whence it is delivered to the galley K, and the matrices are pushed off the second elevator bar J¹ to the distributor box from which they pass to the distributing mechanism proper for delivery to their respective magazine channels.

So far as described, the parts, their construction and mode of operation, except as hereinafter pointed out, are or may be the same as those embodied in the commercial linotype machine, and in themselves constitute no part of the present invention.

Resting on the magazine A is a composing tray A⁴, wherein the special matrices are stored, the tray for this purpose being provided with a plurality of small compartments a for the different characters, and a long compartment a¹ extending completely across the tray at the upper edge thereof to which the matrices are automatically returned after a casting operation. The tray A⁴ is removable and interchangeable with other trays for the different fonts, which when not in use are stored in a suitable cabinet near the machine from which the operator may select the tray of the font desired. In the composition of the special matrices, the operator preferably selects the matrices from the long compartment a¹, that is, those which have been returned after circulating through the machine, for in this way there will always be sufficient room in the compartment to permit transfer of the matrices from the second elevator J without requiring the matrices to be distributed to their respective compartments while the operator is at work.

The standard "head letter" matrices X which are stored in the magazine A are each formed as usual (see Fig. 9) with upper and lower projecting ears x¹, x², a V-shaped distributing notch x³, and an intaglio character x⁴ in its rear edge, the upper ends of the lower projecting ears x² constituting alining surfaces x⁵ by which the matrix characters are alined with the mold slot. As these matrices enter the assembler C in the course of composition, they are supported on the lower rail c¹, which will determine their proper casting level. As the improved machine is designed chiefly for use with standard head letter matrices as well as with special head letter matrices, the transporter F is designed to be arrested at a level corresponding to the normal upper level of the commercial linotype machine, which is the proper casting level for the standard head letter matrices, and also at a higher level to present the special head letter matrices at their proper casting level. In the embodiment illustrated, no provision is made for presenting regular matrices at a level corresponding to the normal lower level of the commercial machine.

The regular two letter matrices Y may be used however, when it is desired to cast a solid line of italics, since such matrices when so used, are supported during composition on the lower rail c¹ of the assembling elevator, and are presented by the transporter to the mold at the same level as the "head letter" matrices. These matrices are each formed as usual with upper and lower projecting ears y¹ and y², a V-shaped distributing notch y³, and superposed intaglio characters y⁴,

y⁵ in their rear edges, the upper ends of the lower projecting ears y² presenting alining surfaces y⁶, similar to the alining surfaces x⁵ of the matrices X.

The longer special matrices Z are each formed with upper projecting ears z¹, corresponding to the upper ears x¹ of the matrices X, a lower projecting ear z² arranged on the rear edge and with its upper face presenting an alining surface z³ by which the matrix characters are alined with the mold slot, and a lower projecting ear z⁴ on the front edge but arranged higher up than the ear z² so as to stand at the same distance from the top as the corresponding ears x² of the standard matrices X. By thus positioning the ear z⁴, the special matrices Z may be supported during composition on the lower rail c¹ of the assembling elevator C and transferred at such lower level to the first elevator without altering the construction of the latter. Each of the matrices Z is also equipped at its upper end with a V-shaped notch z⁵ and opposed teeth z⁶ at the top of the notch, so as to permit the matrices to be transferred to and supported by the second elevator bar, but except for the single pair of teeth z⁶ the notches z⁵ are devoid of distributing teeth, since no sorting of the matrices is required in transferring them to the long compartment a¹ at the upper edge of the storage tray A⁴.

When the standard matrices X or Y are composed in the assembling elevator C, the star-wheel (not shown) forces the first matrix of the line against a vertical finger c carried by the line resistant slide C³, and as subsequent matrices are composed in line, the slide is moved to the left, the finger at all times serving to provide the necessary support for the end of the line. The slide C³ is moved to the left against the tension of a spring C⁴ acting upon the slide through an intermediate pivoted lever C⁵ having its lower end connected to the slide at its right end by a connecting flexible link C⁶.

As the slide is displaced to the left during the composition of the line, it is held in its displaced position by a brake C⁷ consisting of a pair of brake shoes c² engaging the upper and lower edges of the slide, and carried at the lower end of a lever c³ pivotally mounted on the front frame B². The brake shoes c² are normally held in contact with the slide by a spring c⁴ pulling on the brake lever c³ at its lower end, and anchored to a bracket likewise mounted on the frame B².

When the assembling elevator C has been raised to its uppermost position to permit transfer of a composed line, means are actuated to release the brake C⁷, rendering the spring C⁴ effective to return the slide C³ to its normal position. Such means include a bell crank lever c⁵ pivoted to the frame B² and having the end of its upwardly extending leg engaging the brake lever c³ through an interponent c⁶ pivoted on said brake lever (see Fig. 12), and also a horizontal trip lever c⁷ likewise pivoted to the frame and having its left end positioned in the path of a shoulder c⁸ on the assembling elevator. The trip lever c⁷ at its right end is adapted to engage the underlying substantially horizontal leg of the bell crank lever c⁵, so that when the assembling elevator C is raised to permit transfer of the line, the shoulder c⁸ rocks the lever c⁷, causing the brake to be tripped as the bell crank lever c⁵ engages the interponent c⁶ and forces the brake lever c³ at its lower end to the left (Fig. 11).

During hand composition of the special mat-

rices Z however, the operator will first desire to set the length of the line and maintain the setting during the composition of subsequent lines. This is accomplished by rendering the trip lever c^7 and the bell crank lever c^5 ineffective to release the brake when the assembling elevator is raised to transfer the line. Such conditions are brought about by removing the interponent c^6 from the path of the bell crank lever merely by turning it to the position shown in Fig. 12. With this setting, the movement of the trip and bell crank levers is not sufficient actively to engage the brake lever c^3 , and in consequence the brake is not released and the line resistant slide retains its setting when the assembling elevator returns to normal position. The active and inactive positions of the interponent c^6 are determined by a stud c^8 , projecting rearwardly from the face of the interponent and in either of its positions engaging the edge of the brake lever.

After a line has been composed in the assembling elevator C, it is transferred to the transporter or first elevator F through the intermediate channel D, which includes front and rear walls D^1 , D^2 , each presenting an upper rail d for supporting the matrices by their upper ears during transfer, and a lower groove d^1 in the front wall D^1 for accommodating the lower projecting ears of the matrices.

In the improved machine, the channel D is provided with a stop D^3 adjustable to two different positions, in either one of which one form of matrices is permitted to be transferred to the transporter F, and the other form prevented from being transferred thereto. The stop member D^3 consists of a vertical leg d^2 slidably mounted in a groove provided in the rear wall D^2 of the intermediate channel, and a horizontal portion d^3 extending forwardly above the vise cap and presenting a tongue d^4 , whereby it may be readily adjusted to either position by the operator. The horizontal leg d^3 is provided with a notch d^5 in its lower surface to clear the lower frame member of the intermediate channel. The vertical leg at its upper end has a projecting lug d^6 to cooperate with the lower rear projecting ears of the matrices, and when the adjustable stop member D^3 is in its lowermost position (see Figs. 15 and 17), said lug will be located in the path of the ears z^2 of the special matrices Z, thus preventing their transfer to the transporter; whereas the ears x^2 of the standard matrices X or Y will clear the top of the lug, thus permitting their transfer to the transporter, as shown by dotted lines in Fig. 17. When the adjustable stop D^3 is in its upper position, its projecting lug d^6 will lie in the path of the rear projecting ears of the matrices X or Y, but will be above the level of the ears z^2 of the special matrices Z, (see Fig. 16), thus preventing transfer of the former, but permitting transfer of the latter.

It will be recalled that the standard "head letter" matrices X or the standard two-letter matrices Y when a solid line of italics is to be cast, are presented to the mold at the lower level, whereas the special matrices Z are presented to the mold at the upper level. This is brought about by arresting the first elevator F in different vertical positions, as determined by stops on the vise cap O^1 . The first elevator, as usual, includes a long vertical member F^1 slideable in the vise frame O, a top portion F^2 overhanging the vise cap, and a head portion secured 75 to the overhanging top portion and including

front and rear side walls F^3 , F^4 and an intermediate spacing block F^5 at the left end. The elevator head portion, like the intermediate channel, is provided with a pair of upper rails f common to both the special and standard matrices, and which support both by their upper ears. The front wall also is provided with a groove f^1 common to both the special and the standard matrices, and which accommodates their lower ears. 10

When the transporter F occupies its normal position of rest, the supporting rails f are adapted to register, respectively, with the rails d of the intermediate channel, and when the assembler C is raised to transfer position, the lower rail c^1 of the assembler is adapted to register with the corresponding groove d^1 of the channel. Consequently, the lines, composed of either the standard or the special matrices will be properly supported and sustained in their transfer from 15 the assembler C through the intermediate channel D into the transporter F.

Upon delivery of the matrix line to the transporter F, the latter descends to the casting position, where it is supported at the proper level 20 on the vise cap O^1 to locate the matrices of the line in operative relation to the selected mold. The mold G^1 shown in Fig. 13 is for the special matrices Z and comprises generally a fixed body portion g screwed fast to the mold disc G, a cap portion g^1 adjustable toward and from said body portion, and a pair of intermediate end walls or liners g^2 anchored to the cap and the body portions. The mold G^2 (Fig. 15) for the standard "head letter" matrices X is similar, except 30 for size, and both molds G^1 and G^2 present an alining rib g^3 which cooperates with the alining surfaces of the lower projecting ears of the matrices when the disc G is advanced from the rear to the casting position. 40

When the proper mold has been selected, the transporter F is arrested, in its descent, in the proper casting position and the vise automatic operated by a pair of screws f^2 , f^3 , mounted in the transporter overhang F^2 . The screw f^2 banks 45 against a slide O^2 on the vise cap O^1 or on a stud o carried by the slide, whereas the screw f^3 banks against a plate o^1 overlying the top of the vise automatic rod o^2 or against a stud o^3 projecting from the upper face of the plate o^1 , 50 depending upon the position of the slide O^2 . Thus when the slide O^2 is adjusted to the right, the banking studs o , o^3 will be in position to operate with the screws f^2 , f^3 to arrest the transporter at its upper level and operate the vise 55 automatic, whereas when the slide is adjusted to the left, the screws f^2 , f^3 will bank directly against the slide O^2 and the plate o^1 respectively, to arrest the transporter at the lower level and operate the vise automatic. 60

The slide O^2 is pulled to the right by a spring O^3 anchored to the vise cap, and its position is automatically determined by the position of the adjustable line stop D^3 associated with the intermediate channel. Thus, when the adjustable stop is in its upper position, where it prevents transfer of the standard matrices X or Y and permits transfer of the special matrices Z in the manner previously described, the stop D^3 70 clears the slide O^2 which is automatically drawn to the right by the spring O^3 until it banks against a stud o^4 on the vise cap, in which position the studs o , o^3 are in registry with the screws f^2 , f^3 carried by the transporter F, so as to arrest 75

the latter at the upper level required for the special matrices (see Fig. 14).

To adjust the stop D³ to its lowermost position, where only the standard matrices can be transferred, the slide O² is manually pulled to the left against the tension of the spring O³, and the stop pushed downwardly into the path of the slide, which thus banks against the lower end of the stop. In this position of the slide O², the screws 10 f², f³ in the transporter will bank directly on the slide and the plate o¹ associated with the vise automatic, respectively, the transporter thus being arrested at the lower level as required for the standard matrices X or Y. A pair of holes f⁴, f⁵ is provided in the overhanging portion of the transporter to accommodate the studs o, o³ when the slide is adjusted to the left. The slide O² is provided with a pin O⁴ on its upper face to facilitate its manual adjustment.

The devices just described automatically provide for arresting the transporter at the proper casting level for the form of matrices to be transferred thereto, but it may happen that the operator, through inattention or mistake, will not select the proper mold for cooperation with the matrices. The means now to be described bring about the arrest of the transporter in advance of the casting level, in the event that an improper mold is selected. The arrest of the transporter in such abnormal positions prevents the operation of the vise automatic, thus stopping the machine and preventing damage and metal "squirts" which would otherwise result. Such means include a slidable member L mounted on the transporter head and adjustable to either of two positions, depending upon the adjustment of the slide O². The member L consists of front and rear plates L¹, L² joined together at the top, a downwardly projecting finger L³ at the rear, a U-shaped plate L⁴ secured to the front plate, and a stud L⁵ at the top to facilitate adjusting it from one position to another.

The finger L³ at the rear is adapted to cooperate with variant banking blocks G³, G⁴ associated with the different molds G¹, G² and positioned at the left thereof, whereas the U-shaped plate in front is adapted to cooperate with a banking block o⁴ on the vise cap and another banking block o⁵ on the slide if the member L is not properly adjusted with reference to the slide O². The proper positions of the member L for the different forms of matrices when the proper mold has been selected therefor, are shown in full lines in Figs. 14 and 15.

The banking block G³ associated with the large or special mold G¹, is comparatively wide and has a raised banking surface g⁴ at the left, and a lower recessed portion g⁵ at the right adjacent the mold. The banking block G⁴ associated with the smaller or standard mold G² is narrower than the block G³ associated with the special mold, and has a high banking surface g⁶ adjacent the mold. Furthermore, it will be observed that when the slide O² is in its rightmost position to arrest the transporter at the upper level, the banking blocks o⁴ and o⁵ on the vise cap and the slide are in spaced relation, permitting the left leg l of the U-shaped plate L⁴ to pass between them when the member L is adjusted to the right as shown in Fig. 14. When the slide O² is in its leftmost position, the banking blocks o⁴, o⁵ are close together, permitting the legs l, l¹ of the U-shaped plate L⁴ to straddle the blocks when said member is adjusted to the left (Fig. 15). Thus, if the member L is in its proper position,

and the proper mold has been selected, the transporter will, in the case of the large or special matrices Z (Fig. 14), descend until it is arrested at the upper level by the banking stud o on the slide, the left leg l of the member L passing between the banking blocks o⁴, o⁵ on the vise frame and slide, and the depending finger L³ passing into the recess g⁵ provided in the banking block G³. Likewise, if the proper mold has been selected for the standard matrices X, and the member L has been adjusted to its leftmost position, the transporter will descend to its lower level, where it is arrested by the slide O², the depending finger L³ under such conditions clearing the banking block G⁴ on the mold G² and the U-shaped member L⁴ straddling the banking blocks on the vise cap and slide.

Suppose now that the operator has adjusted the member L to its proper position, as determined by the setting of the slide O², but, through inattention, has failed to select the proper mold. Thus, if the slide O² and the member L are in the position shown in Fig. 14, but the mold G² shown in Fig. 15 has been selected, the transporter F will be arrested in the abnormal position shown in Fig. 14 by the finger L³ banking against the block G⁴ associated with said mold. The arrest of the transporter in this position will prevent the operation of the vise automatic and the machine will stop automatically, permitting the operator to make the proper adjustments. Likewise, if the slide O² and safety member L are adjusted to their proper positions, as shown in Fig. 15, but the mold shown in Fig. 14 is selected through mistake, the transporter F will again be arrested in an abnormal position by the finger L³ banking against the high portion g⁶ of the block G³ associated with said mold with the same results as before.

The machine is substantially "fool-proof" because the adjustment of the safety member L must be made regardless of whether or not the proper mold has been selected. Thus, if the slide O² is adjusted to the right as shown in Fig. 14, but the safety member L remains in the leftmost position shown in dotted lines, the transporter will be arrested in an abnormal position by the right leg l¹ of the U-shaped member L⁴ engaging the banking block o⁵ on the slide whether or not the proper mold has been selected, thus indicating to the operator that the safety member L must be adjusted. Likewise, if the slide O² is adjusted to the left as shown in Fig. 15, but the safety member L remains in the rightmost position shown in dotted lines, the transporter will again be arrested in an abnormal position by the left leg l of the U-shaped member engaging the banking block o⁵ on the slide. Thus, it will be observed that the safety devices are so constituted that once the operator has determined on the form of matrices to be used, and has made the proper adjustment of the stop D³ associated with the intermediate channel, the machine will be prevented from completing the casting operation until all of the proper adjustments have been made.

After the casting operation has been completed, the mold disc recedes, and the transporter F ascends to its uppermost level to bring the matrices in registry with the transfer slide H, the disc in the meantime making a three-quarter turn to carry the slug to ejecting position in registry with the trimming knives. The ejecting blade comes forward to force the slug between the trimming knives into a chute leading

to the galley K. The matrices are transferred to the bar J¹ carried by the second elevator J and the spacebands, if any have been used, returned to the spaceband storage magazine M. In the embodiment shown, the second elevator includes a lever J² pivoted to the machine, a link J³ connecting the lever J² with a second lever J⁴ pivoted at the rear of the machine and operated at the proper time from the usual cam mounted on the cam shaft. It further includes a small lever J⁵ pivoted at the end of the second elevator lever J² and anchored in position by a spring J⁶. The lever J⁵ has limited movement about its pivot, as determined by a pair of spaced radial projections j and a stud j¹ on the lever J². The small lever J⁵ carries the usual plate J⁷ to which the second elevator bar J¹ is attached.

The machine is also provided with a shifter bar J⁸ equipped with a pusher finger j² and which operates as usual when the second elevator has brought the matrices in registry with the distributor box, to transfer said matrices from the second elevator bar J¹ to the distributor box. In the improved machine however, the distributor shifter bar is provided with a second pusher finger j³ carried by the same bracket j⁴ as the usual pusher finger j² but arranged directly in front thereof.

The second elevator J is adapted to be arrested at two positions, i. e., in its normal or rearward position to bring the standard matrices in registry with the usual distributor box for transfer thereto, and in a forward or advance position when the special matrices Z are used to bring said matrices in registry with a channel N leading to the long compartment a¹ at the upper edge of the tray A⁴. When the elevator is arrested in the advance position, the auxiliary pusher finger j³ transfers the matrices Z from the second elevator bar J¹ into the channel N. The second elevator J is arrested in its normal or rearward position by the plate J⁷ engaging in a notch j⁸ on the frame, and in its forward position by a hand operable lever J⁹ pivoted to a bracket J¹⁰ extending rearwardly from the frame, and having a forwardly projecting nose j⁶ arranged to be swung into active position behind the end of the second elevator lever J² (Fig. 20). The active and inactive positions of the lever J⁹ are determined by a stud j⁷ against which the edges of the upper and the lower arms of the lever J⁹ bank in the respective positions, a spring detent j⁸ being mounted in the lever and engaging in one or another of a pair of recesses j⁹ in the face of the bracket J¹⁰ to hold the lever in either position.

As the matrices are carried by and transferred from the second elevator J in a vertical position, some means must be provided for gradually turning the matrices from a vertical plane into the plane of the angularly positioned storage tray A⁴, so that the matrices may be guided into the long compartment a¹ at the upper edge thereof. The means for this purpose (Figs. 18, 21) is the aforementioned channel N supported by a bracket N¹ attached to the main frame, and including a top n, a bottom n¹, a rear wall n², and front retaining plates n³ for guiding the matrices in their passage through the channel, but leaving an opening n⁴ for access to the matrices. About midway of its length, the bottom n¹ of the channel is depressed to drop the matrices into the second half thereof, which is twisted to impart a gradual turn to the matrices in their passage through the channel into the plane of the storage tray A⁴ in the manner shown. As a result of this

arrangement, the matrices are guided from the second elevator bar J¹ through the channel N and into the long compartment a¹ at the upper edge of the tray.

As mentioned heretofore, the slug after being cast, is brought to ejecting position by a three-quarter rotation of the mold disc G, and is thereafter pushed between a pair of knives into a chute K¹, from which it is delivered to the galley K mounted on the vise frame O at the front of the machine. As a rule, the left hand knife (not shown) is stationary, but the right hand knife (likewise not shown) is adjustable in accordance with the thickness of the slug, so that the side faces thereof may be properly trimmed. The right hand knife is carried by a sliding frame K² adjustable by means of a rotatable plate K³ carrying a series of banking studs k of different lengths which bank against the frame and determine the setting of the knife, all of which is more fully described in Patent No. 1,782,468 issued to A. W. F. Guest.

The chute K¹ into which the slugs are ejected, includes generally a rear curved plate k¹, a pair of sides k², k³, and a hinged front plate k⁴, whereby the slugs are guided into the galley. The left side k² of the chute is stationary, but the right side k³ is adjustable to accommodate slugs of different thicknesses, and for this purpose is carried by the right hand knife frame K², so as to be adjusted to its proper position along with the adjustment of the knife.

After the slug has been delivered to the galley K, it is pushed to the left by a stacker K⁴ to make room for the slug next to be delivered. The stacker K⁴ includes a pusher plate k⁵, mounted on a lever k⁶ pivoted to the vise frame O, and having a downwardly extending arm arranged to be engaged by a fore-and-aft stud k⁷ fast to the vertical transporter slide F¹ at its lower end. As the transporter F descends from its normal position to present a line of matrices to the mold, the stud k⁷ engages the lower arm of the stacker lever k⁶, turning it slightly, to cause the pusher plate k⁵, to push the slug, previously delivered to the galley, to the left to make room for the slug next to be delivered. As the transporter ascends to its uppermost position after the casting operation, the stacker K⁴ is permitted to return to its normal position under the influence of a spring (not shown) or by gravity.

In the improved machine, the stroke of the stacker member K⁴ is regulated to accommodate slugs of different thicknesses, so as to prevent the tendency of thinner slugs to fall over on their sides before the stacking operation, due to the absence of lateral support in the galley K. The arrangement for this purpose includes a curved finger k⁸ carried by the adjustable right hand guide plate k³ of the chute, and which engages behind a projecting lug k⁹ on the pusher plate k⁵, thus determining the arc through which the stacker lever k⁶ is permitted to move. Thus, when the machine is set to cast thick slugs, the stacker K⁴ will be actuated from normal position to the position shown by dotted lines in Fig. 3, or through a distance corresponding to the thickness of a large slug, whereas, when the machine is set to cast a thinner slug, said stacker will be actuated through a smaller distance to the position shown in dotted lines in Fig. 4, or through a distance corresponding to the width of a narrow slug. With this arrangement, it will be observed that the slug upon entering the galley will always

have lateral support, thus obviating any tendency for it to topple over on its side.

In view of the previous description, it is believed the invention will be readily understood without entering into a further description of the operation of the machine.

In the accompanying drawings the invention has been shown merely by way of example and in preferred form, and obviously many variations and modifications may be made therein which will still be comprised within its spirit. It is to be understood, therefore, that the invention is not limited to any specific form or embodiment, except in so far as such limitations are specified in the appended claims.

Having thus described my invention, what I claim is:

1. In a typographical casting machine adapted to employ matrices of different forms, the combination of a transporter for presenting a composed line of matrices to the mold, and means adjustable to different operative positions at the will of the operator for preventing the delivery of one or another of the forms of matrices to the transporter.

2. In a typographical casting machine adapted to employ matrices of different lengths, the combination of a transporter for presenting a composed line of matrices to the mold, a stop member adjustable to different operative positions and adapted in one of its adjusted positions to prevent delivery to the transporter of matrices of one length and in another of its adjusted positions to prevent delivery to the transporter of matrices of another length.

3. A typographical casting machine adapted to employ matrices of different forms, the combination of a transporter for presenting a composed line of matrices to the mold, an assembler in which the line is composed, a transfer channel between the assembler and the transporter, and a stop associated with the transfer channel and adjustable to different operative positions and adapted in one of its adjusted positions to prevent transfer to the transporter of matrices of one form, and in another of its adjusted positions to prevent transfer to the transporter of matrices of another form.

4. In a typographical casting machine adapted to employ matrices of standard length, having projecting ears adjacent the lower ends thereof and special matrices of greater than standard length having similar projecting ears adjacent the lower ends thereof, the combination of a transporter for presenting a composed line of matrices to the mold, an assembler in which the line is composed, a transfer channel between the assembler and the transporter, and a stop associated with the transfer channel and adjustable to different operative positions and adapted in either of its adjusted positions to cooperate with the projecting ears of matrices of one length to block their transfer to the transporter while permitting transfer of matrices of the other length.

5. In a typographical casting machine employing matrices of different forms adapted to be presented to the mold at different casting levels, the combination of a transporter for presenting a composed line of matrices to the mold, said transporter being constructed to support the matrices of the different forms at a common level therein, arresting devices for stopping the transporter at one or another of the different casting levels according to the form of ma-

trices in use, and means for preventing transfer to the transporter of matrices of a form other than that for which said arresting devices are adjusted.

6. In a typographical casting machine employing matrices of different forms adapted to be presented to the mold at different casting levels, the combination of a transporter for presenting a composed line of matrices to the mold, said transporter being constructed to support the 10 matrices of the different forms at a common level therein, arresting devices for stopping the transporter at one or another of the different casting levels according to the form of matrices in use, and a stop having a plurality of different adjustments depending upon the arresting devices in use and acting to prevent transfer to the transporter of matrices of a form other than that for which said arresting devices are adjusted. 15

7. In a typographical casting machine employing matrices of different lengths and adapted to be presented to the mold at different casting levels, the combination of a transporter for presenting a composed line of matrices to the mold, adjustable means for arresting the transporter at different casting levels according to the length of the matrices in use, and a stop having different operative adjustments depending upon the arresting devices in use and acting to prevent transfer to the transporter of matrices 30 of a form other than that for which the arresting devices are adjusted. 25

8. In a typographical casting machine adapted to employ matrices of standard length and special matrices of greater than standard length, 35 said different length matrices being adapted to be presented to the mold at different casting levels and each having projecting ears adjacent the lower ends thereof, the combination of a transporter for presenting a composed line of 40 matrices to the mold, an assembler in which the line is composed, a transfer channel between the assembler and the transporter, adjustable arresting devices for stopping the transporter at one or another of the different casting levels 45 depending upon the matrices in use, and a stop associated with the transfer channel and having different adjusted positions depending upon the arresting devices in use, and acting in either of its adjusted positions to cooperate with the projecting ears of the matrices other than those for which the arresting devices are set and thus prevent their transfer to the transporter. 50

9. A typographical casting machine adapted to employ matrices of two different forms, a 55 transporter for presenting a composed line of matrices to the mold, an assembler in which the line is composed, a transfer channel between the assembler and transporter, a stop adjustable to two different positions and adapted in one position to permit one form of matrices only to be transferred to the transporter while preventing transfer of the other form, and vice versa, and adjustable devices for arresting the transporter at different casting levels for the different forms 60 of matrices, the proper setting of said arresting devices for the matrices to be transferred being determined automatically by the adjustment of said stop. 65

10. A typographical casting machine adapted 70 to employ matrices of two different forms, a transporter for presenting a composed line of matrices to the mold, an assembler in which the line is composed, a transfer channel between the assembler and transporter, a stop associated with 75

the transfer channel and adjustable to two different positions, being adapted in one of its adjusted positions to permit one form of matrices only to be transferred to the transporter, while preventing transfer of the other form, and vice versa, and adjustable devices for arresting the transporter at different casting levels for the different forms of matrices, the proper setting of said arresting devices being determined automatically by the adjustment of said stop.

11. A typographical casting machine adapted to employ matrices having lower projecting ears adapted to stand at different levels during assembly, a transporter for presenting a composed line of matrices to the mold, an assembler in which the line is composed, a transfer channel between the assembler and transporter, a stop associated with the transfer channel and adjustable to different operative positions and adapted in one or another of its adjusted positions to lie in the path of the differently located projecting ears of the matrices, and adjustable devices for arresting the transporter at different casting levels depending upon the level of the projecting ears of the composed matrices, the setting of said arresting devices being automatically determined by the position of the adjustable stop.

12. In a typographical casting machine adapted to employ matrices of different forms, the combination of a plurality of molds selectable according to the form of matrices to be employed, a transporter for presenting a composed line of matrices to the selected mold, said transporter being constructed to support the matrices of the different forms at a common level therein, adjustable means for permitting one form or another of the matrices to be transferred to the transporter, and safety devices settable in accordance with the adjustment of said adjustable means and acting to permit or prevent presentation of the line to the mold depending upon the selection of the proper mold for the matrices transferred.

13. In a typographical casting machine, adapted to employ matrices of different forms, the combination of a plurality of molds selectable according to the form of matrices to be employed, a transporter for presenting a composed line of matrices to the selected mold, said transporter being constructed to support the matrices of the different forms at a common level therein, adjustable means for permitting one form or another of the matrices to be transferred to the transporter, and safety devices settable in accordance with the adjustment of said adjustable means and acting to stop the machine when an improper mold has been selected for use with the form of matrices transferred.

14. A combination in accordance with claim 12, wherein the safety devices include variant banking blocks associated with the respective molds, and an adjustable cooperative element carried by the transporter.

15. In a typographical casting machine adapted to employ matrices of different forms, the combination of a plurality of molds selectable according to the form of matrices to be employed, a transporter for presenting a composed line of matrices to the selected mold, adjustable means for permitting one form or another of the matrices to be transferred to the transporter, safety devices acting when properly set to prevent presentation of the line to the mold when an improper mold has been selected for use with the form of matrices transferred, said safety de-

vices including variant banking blocks on the respective molds and a settable cooperative element on the transporter, and means acting to stop the machine when said cooperative element is improperly set with reference to the adjustable means.

16. In a typographical casting machine adapted to employ matrices of different forms, the combination of a plurality of molds selectable according to the form of matrices to be employed, a transporter for presenting a composed line of matrices to the selected mold, an adjustable stop acting in different adjusted positions to prevent transfer to the transporter of one form of matrices while permitting transfer of the other, and safety devices including adjustable means carried by the transporter and having one or another proper position of adjustment depending upon the position of the adjustable stop, said means being arranged to stop the machine when improperly positioned with reference to the position of the adjustable stop, and when properly positioned, to prevent presentation of the line to the mold if an improper mold has been selected for the form of matrices transferred to the transporter.

17. A typographical machine in accordance with claim 12, wherein the different forms of matrices employed are matrices of standard length and matrices of greater than standard length, both forms having projecting alining ears adjacent the lower ends thereof, which ears in the different forms stand at different levels during transfer, and wherein the adjustable means referred to comprises a stop adapted in its different adjusted positions to lie in the path of the ears of one of the forms of matrices to prevent their transfer while permitting transfer of the other form.

18. In a typographical casting machine adapted to employ matrices of different forms, the combination of a plurality of molds selectable in accordance with the form of matrices to be used, a transporter for presenting a composed line of matrices to the selected mold, an adjustable stop adapted in its different adjusted positions to permit the transfer to the transporter of one form of matrices while preventing transfer of the other, adjustable devices for arresting the transporter at one casting level or another depending on the form of matrices employed, and safety devices for preventing the presentation of the line to the mold when an improper mold has been selected, said safety devices including variant banking blocks associated with the respective molds and a cooperative element carried by the transporter, said cooperative element having different operative positions depending upon the form of matrices employed, the proper adjustment of the arresting devices and the proper position of the cooperative element being automatically determined by the position of the adjustable stop.

19. In a typographical composing machine, the combination of an assembler wherein matrices having projecting ears are adapted to be composed with their ears standing at different levels, a vertically movable transporter for presenting a composed line of matrices to the mold, said transporter being constructed to support the matrices of the different forms at a common level therein, a transfer channel intermediate the assembler and the transporter, and adjustable means associated with the transfer channel and arranged to cooperate with the projecting ears

of the matrices to prevent or permit their transfer depending upon the level of said projecting ears.

20. In a typographical composing machine, the combination of an assembler wherein matrices having projecting ears are adapted to be composed with their ears arranged at different levels, a vertically movable transporter for presenting a composed line of matrices to the mold, devices for arresting the transporter at different casting levels depending upon the level of the ears of the composed matrices, a transfer channel between the assembler and transporter, and adjustable means associated with the transfer channel and arranged to cooperate with the projecting ears of the matrices to prevent or permit their transfer depending upon the level of the ears, said adjustable means in turn determining the proper relation of the arresting devices with the transporter for the matrices transferred.

21. A type or matrix of greater than standard length formed at its lower end with projecting ears, one located higher up on the matrix than the other.

22. A type or matrix of greater than standard length and formed on its non-casting edge with a lower projecting ear located at the standard distance from the upper end of the matrix, for the purpose described.

23. A type or matrix of greater than standard length formed on its non-casting edge with a lower projecting ear located at the standard distance from the upper end of the matrix and on its casting edge with a lower projecting ear located at greater than standard distance from the upper end.

24. A type or matrix of greater than standard length formed at the top with a pair of ears projecting from the opposite edges thereof, and at its lower end with an alining ear projecting from the casting edge at the bottom of the matrix and with a supporting ear projecting from the non-casting edge at a definitely higher level than that of the alining ear.

25. A typographical machine equipped with regular matrices of standard length and special matrices of greater than standard length and provided with an assembling elevator having the usual superposed front rails for supporting the regular matrices, the special matrices extending below the lowermost supporting rail but having projecting ears spaced above their lower ends and adapted to engage one of said elevator rails.

26. A typographical machine equipped with regular matrices of standard length and special matrices of greater than standard length and provided with an assembler elevator having the usual front rail but devoid of the usual companion rear rail for supporting the regular matrices at the lower level, the special matrices having projecting ears in their front edges spaced the same distance from the top as the corresponding ears on the regular matrices and adapted to engage said front rail whereby the matrices are supported in the assembler solely by the engagement of said ears and said front rail.

27. In a typographical composing machine, the combination of an assembling elevator, in which a line of matrices is composed, a line resistant slide adapted to support the end of the composed line and being arranged to yield against the action of resilient means as the individual matrices are composed in line, a brake normally resisting the return of the assembler slide, means operated by the assembling elevator as the line is trans-

ferred to release the brake, and means for rendering said releasing means operative or inoperative at the will of the operator to permit or prevent the return of the slide to normal position.

28. In a typographical composing and distributing machine employing standard matrices for machine composition and special matrices for hand composition, the combination of a magazine in which standard matrices are stored, a storage tray for the special matrices, an assembling elevator wherein the matrices are composed in line, a transporter for presenting the composed line to the mold for casting, a second transporter to which the line is transferred after casting, a distributor for returning the standard matrices to their magazine, a guideway leading to the storage tray, and means for arresting the second transporter in line transfer relation to said distributor or said guideway, according to the matrices in use.

29. In a typographical composing and distributing machine employing standard matrices for machine composition and special matrices for hand composition, the combination of a magazine in which standard matrices are stored, a storage tray for the special matrices arranged above said magazine, an assembling elevator wherein the matrices are composed in line, a transporter for presenting the composed line to the mold for casting, a second transporter to which the line is transferred after casting, a distributor for returning the standard matrices to their magazine, a guideway leading to the storage tray, means for arresting said second transporter in its normal position to permit transfer of the standard matrices to the distributor, and means for arresting said transporter in advance of its normal position to permit transfer of the special matrices to the guideway leading to the storage tray.

30. A typographical composing and distributing machine in accordance with claim 28, wherein a pusher member is provided for transferring the matrices from the second transporter, said pusher member having a pair of fingers either one of which is operative depending upon whether the standard matrices are to be delivered to the distributor or the special matrices to their storage tray.

31. In a typographical composing and distributing machine employing special matrices for hand composition, and provided with an assembling elevator, a first elevator for presenting a composed line of matrices to the mold, and a second elevator to receive the composed line after casting from the first elevator, the combination of an inclined storage tray for the special matrices, a vertically disposed channel into which the special matrices are transferred from the second elevator, and a connecting channel between the vertical channel and the inclined storage tray constructed and arranged to translate the matrices from a position coincident with the vertical channel to a position coincident with the inclined tray.

32. An improved galley stacker for a slug casting machine having means for presenting a line of matrices to the mold, means for casting a slug against the line, a slug ejector, and adjustable trimming knives for trimming the ejected slug, said galley stacker comprising a pusher member and means for reciprocating the pusher member to push a slug delivered to the galley out of the path of the slug next to be delivered, the length of stroke of the pusher member being controlled by the adjustment of the trimming knives.

33. An improved galley stacker for a slug casting machine having means for presenting a line of matrices to the mold, means for casting a slug against the line, a slug ejector, right and left trimming knives for trimming the ejected slug, and means for adjusting the right hand knife toward and from the left hand knife, said galley stacker comprising a pusher member and means for reciprocating the pusher member to push a slug delivered to the galley out of the path of the slug next to be delivered, the length of stroke of the pusher member being automatically determined by the adjusted position of the right hand knife.
- 10 34. In a slug casting machine having means for presenting a composed line of matrices to the mold, means for casting a slug against the line, a

slug ejector, right and left knives for trimming the ejected slugs, and means for adjusting the right hand knife toward and from the left hand knife, the combination of a galley for receiving the ejected slugs, a stacker comprising a pusher member, means for reciprocating the pusher member to push a slug delivered to the galley out of the path of the slug next to be delivered, a chute for guiding the ejected slug to the galley, said chute having a side wall adjustable in accordance with the position of the right hand knife, and means associated with the side wall and cooperating with the pusher member to adjust the stroke thereof in accordance with the thickness of the slugs delivered.
